UNITED STATES PATENT OFFICE

CARL HERDEMERTEN, OF NIEDERSCHREIBERHAU, GERMANY, ASSIGNOR TO FIRM
MINIMAX ACT.-GES., OF BERLIN, GERMANY

APPARATUS FOR CHARGING AND CLEANING BOREHOLES BY MEANS OF COMPRESSED AIR

Application filed May 9, 1927. Serial No. 190,121.

For charging bore-holes to be used for blasting-work in mining operations apparatus are used having the material to be forced into the bore-hole, generally rock-dust, enclosed in a storage-receptacle from which the pulverulent material is forced into the bore-hole by means of compressed air, said receptacle being connected up to a compressed-air vessel or other supplying means. There is formed in the said receptacle a separate compartment by means of a perforated wall, and the compressed air is introduced into this compartment.

The fact has been ascertained that the effect of apparatus of the kind stated in the preceding paragraph is not so perfect as desired as, owing to the compressed air acting solely by pressing or shoving, a part of the pulverulent material, or of the rock-dust respectively, is again driven out of the bore-hole.

The object of the present invention is to obviate the drawback mentioned, and I attain the effect desired by designing the apparatus in such a manner that the compressed air exerts not only a pressing, but also a sucking action upon the rock-dust. The means to attain this two-fold effect consists therein that the compressed-air compartment in the apparatus or, more precisely, the perforated wall mentioned, is provided with some separate perforations also at the narrowest portion of the rock-dust receptacle where this latter is connected with the pipe leading the dust to and into the bore-hole, the position of said separate perforations being such that the currents of compressed air streaming through them escape practically directly into said pipe, and the effect being, therefore, practically like that of an injector. The rock-dust into which the compressed air is forced through the main perforations of the wall, and which is, besides, subjected to the pressure of the compressed air, is thus, sucked out of the rock-dust receptacle by the separate perforations mentioned, and the bore-hole is now charged in a perfectly reliable manner, without any loss of the rock dust.

The apparatus improved in the manner stated can, however, be used also for clearing

the bore-holes in order either to remove the rock-dust still present in the hole, or the charge of the hole in the case of a failure. As the dust often times contains also quartz it may easily occur that sparks are produced at the bore-hole by the tube, the simple blowing out with a compressed-air pipe is, therefore, inadmissible.

Now, in order to render the apparatus suited also for the blowing-out operation, with complete prevention of the arising of sparks, it is provided with a separate guide-tube, the diameter of which corresponds about to that of the bore-hole, in such a manner, that said guide-tube can be shoved thereinto; besides, the said tube consists of a soft metal so that no sparks can arise when it is scratched at and by the wall of the bore-hole. The dust present in this hole slides no more along the wall of the same but is driven out by the compressed air through that guide-tube. A basin arranged outside the guide-tube near the front end of the same intercepts the dust, gathers it and causes it to fall down to the bottom or into any suitable vessel.

The invention is illustrated diagrammatically and by way of example on the accompanying drawing on which Figure 1 is an axial section through an apparatus designed according to this invention, and Figure 2 is partly a side-view of this apparatus and partly an axial section through a bore-hole with the said guide-tube therein, in connection with a few other parts, this figure being drawn to a reduced scale.

On the drawing, *a* denotes the body of the apparatus, which is preferably funnel-shaped and provided with a suitable cover. In the example shown *c* denotes this cover and *b* a tightening rubber-ring which can be pressed upon the edge of the neck of the body or vessel *a* by means of a somewhat bowshaped member *e* *e*¹ hinged at *d* to a bracket *r* affixed to the top of the vessel *a*, extending over the cover *c*, and forming at its free end a hook *e*² which co-operates with a bow *f* hinged to a grip-forming lever *g* fulcrumed at *g*' to a bracket *s* also affixed to the top of the vessel *a*.

A perforated sheet-metal member *h*' of trough-like cross-section is inserted into the

100

vessel *a* and secured to the wall of the same and forms with the respective wall portion a compartment *h*. The member *h'* is provided with perforations *h''*, and the wall portion concerned is provided with a nozzle *m* into which a cock *m'* is inserted. The nozzle *m* serves for connecting the compartment *h* with a compressed-air supply pipe (not shown). I wish it to be understood that the sheet-metal member *h'* can be attached, instead of to the inner surface of the wall of the vessel *a*, to the outer surface thereof, the perforations *h''* being then provided, of course, in the wall portion instead of in the member *h'*.

A particularly important feature resides, now, in the provision of separate perforations *k* located at the end *a'* of the compartment *a* and having such a position that the currents 20 of compressed air escaping through them stream forth practically directly into the discharge pipe *i* which is, preferably, curved, as shown.

The pipe *i* can be connected with an extension pipe *i'* (Fig. 2) surrounded with a larger pipe *o*, the diameter of which is just a little smaller than the diameter of the bore hole *n*, and which is detachably attached to the pipe *i'* by means of narrow stays *o'*. The tube *o* consists of a soft metal, for instance zinc, so that no sparks can arise when it is shoved into the bore-hole *n*. In front of the tube *o* a basin *p* is affixed to the pipe *i'*, as shown in Fig. 2.

The tube *o* is not required when the rock 35 dust is introduced into the bore-hole. When the dust has been introduced into the vessel *a* the connected tubes *i* and *i'* are introduced into the bore-hole, and the cock *m'* is opened so that the compressed air streams first into 40 the compartment *h* and then further through the perforations *h''* into the vessel *a* where it acts upon the rock-dust in the manner already described. The compressed air streams, however, also through the separate perforations 45 *k* and sucks the dust through the passage *a'*, driving it then through the pipes *i* and *i'* into the bore-hole. The pipes *i* and *i'* are withdrawn by and by according to the progress in the filling of the bore-hole, and 50 the procedure is continued until the bore-hole has been filled in the desired degree.

When then, later on, the bore-hole is to be cleaned or the charge must be removed because of a failure, the tube *o* is shoved upon 55 the tube *i'*, and compressed air is again blown into the bore-hole, the vessel *a* being now, however, empty. The dust is then blown by the compressed air issuing forth from the tube *i'* into the tube *o* and towards and against 60 the basin *p* by which the dust is led downwardly, as already described.

I claim:

1. An apparatus for charging and cleaning bore holes by means of compressed air, comprising, in combination, a receptacle

adapted to receive the pulverulent filling material for the bore-holes, means for supplying the compressed air to said material in said vessel, as well as to the discharge aperture of the latter, a tube extending forth from said discharge aperture and adapted to be introduced into a bore-hole, and another tube encompassing the first-mentioned tube and forming a tubular passage between itself and said first-mentioned tube and having an outer diameter just fitting into a bore-hole, substantially as set forth.

2. An apparatus for charging and cleaning bore holes by means of compressed air, comprising, in combination, a receptacle adapted to receive the pulverulent filling material for the bore-holes, means for supplying the compressed air to said material in said vessel, as well as to the discharge aperture of the latter, a tube extending forth from said discharge aperture and adapted to be introduced into a bore-hole; and another tube consisting of a soft metal unable to produce sparks, and encompassing the first-mentioned tube and forming a tubular passage between itself and said first-mentioned tube and having an outer diameter just fitting into a bore-hole, substantially as set forth.

3. An apparatus for charging and cleaning bore holes by means of compressed air, comprising, in combination, a receptacle adapted to receive the pulverulent filling material for the bore-holes, means for supplying the compressed air to said material in said vessel, as well as to the discharge aperture of the latter, a tube extending forth from said discharge aperture and adapted to be introduced into a bore-hole; another tube encompassing the first-mentioned tube and forming a tubular passage between itself and said first-mentioned tube and having an outer diameter just fitting into a bore-hole, and a basin arranged upon the inner tube in front of the outer one, substantially and for the purpose set forth.

In testimony whereof I affix my signature.
CARL HERDEMERTEN.
